(57) CLAIM

The ornamental design for a model and collectible display case, as shown and described.

DESCRIPTION

FIG. 1 is a front elevational view of the model and collectible display case of the present invention;

FIG. 2 is a rear elevational view of the model and collectible display case of FIG. 1;

FIG. 3 is a left side elevational view of the model and collectible display case of FIG. 1, the right view being a mirror image thereof;

FIG. 4 is a right side elevational view of the model and collectible display case of FIG. 1, the left view being a mirror image thereof;

FIG. 5 is a top plan view of the model and collectible display case of FIG. 1;

FIG. 6 is a bottom plan view of the model and collectible display case of FIG. 1; and,

FIG. 7 is a top, left side perspective view of the model and collectible display case of FIG. 1.

The broken line showing of a car in FIG. 7 is for illustrative purposes only and forms no part of the claimed design.
